PHONOGRAPH SPINDLE ADAPTOR FOR 45 R.P.M.
RECORDS OR SIMILAR ARTICLE

David L. Kahler and Eugene A. Stoner, Decatur, Ill., assignors to General Electric Company, a corporation of New York

Filed Jan. 3, 1969, Ser. No. 15,200

Term of patent 14 years

Int. Cl. D14—01

U.S. Cl. D56—4

FIG. 1 is a side, top and front perspective view of a phonograph spindle adaptor for 45 r.p.m. records, or similar article, showing our new design:

FIG. 2 is a rear, top and side perspective view:

FIG. 3 is a top plan view:

FIG. 4 is a bottom plan view:

FIG. 5 is a side elevational view, the opposite side being substantially a mirror image thereof:

FIG. 6 is a front elevational view; and

FIG. 7 is a rear elevational view thereof.

We claim:

The ornamental design for a phonograph spindle adaptor for 45 r.p.m. records or similar article, substantially as shown.
